[57] **CLAIM**

The ornamental design for a combined bicycle horn, radio and light, as shown and described.

DESCRIPTION

FIG. 1 is a front, right side perspective view of a combined bicycle horn, radio and light showing my new design;

FIG. 2 is a left side elevational view thereof;

FIG. 3 is a rear elevational view thereof;

FIG. 4 is a bottom plan view thereof;

FIG. 5 is a front, right side perspective view thereof with the radio antenna in a raised position;

FIG. 6 is a bottom plan view thereof with the bottom bracket detached to show the radio speaker on the bottom surface of the housing;

FIG. 7 is a front, right side perspective view of a second embodiment of my new design;

FIG. 8 is a left side elevational view thereof;

FIG. 9 is a rear elevational view thereof;

FIG. 10 is a bottom plan view thereof;

FIG. 11 is a front, right side perspective view thereof with the radio antenna in a raised position;

FIG. 12 is a bottom plan view thereof with the bottom bracket detached to show the radio speaker on the bottom surface of the housing.

FIG. 1.

FIG. 2.

FIG. 3.

FIG. 4.

FIG. 5.

FIG. 6.

FIG. 7

FIG. 8.

FIG. 9.

FIG. 10.

FIG. 11.
